UNITED STATES PATENT OFFICE.

DOMINIC SHERLOCK, OF PITTSBURG, PENNSYLVANIA.

FOLDING CLOTHES-DRIER.

No. 844,962.

Specification of Letters Patent.

Patented Feb. 19, 1907.

Application filed March 28, 1905. Serial No. 252,482.

To all whom it may concern:

Be it known that I, DOMINIC SHERLOCK, a citizen of the United States, residing at Pittsburgh, in the county of Allegheny and State of Pennsylvania, have invented a new and useful Improvement in a Folding Clothes-Drier, of which the following is a specification.

This invention relates generally to clothes-driers, and more particularly to an improved construction of folding clothes-drier, the object being to provide an exceedingly simple, cheap, and efficient device which can be quickly and easily set up for the purpose of holding the clothes to be dried and as easily taken apart and folded when not desired for use.

The invention consists in the details of construction hereinafter fully described, and pointed out in the claims.

In the drawings forming a part of this specification, Figure 1 is a perspective view of a clothes-drier constructed in accordance with my invention and set up ready to receive the lines upon which the clothes are to be hung. Fig. 2 is a detail view showing in top plan a portion of the device. Fig. 3 is a detail view, partly in section and partly in elevation, illustrating the manner of locking the legs of the rack together, the section being taken on line 3-3 of Fig. 2. Fig. 4 is a detail view showing in side elevation that portion of the device shown in top plan in Fig. 2. Fig. 5 is a detail perspective view of one end of the connecting-pole with the block arranged thereon, and Fig. 6 is a detail perspective view of the pole without the block.

In carrying out my invention I employ two supporting-legs A, which are adapted to cross each other, as shown, and are provided with a series of hooks B upon their upper portion and to which the clothes-lines are to be connected. Each leg has an eye C adjacent its lower end, which eye is connected by means of a cord D to limit the movement of the said legs apart.

E indicates a connecting-pole, which is intended to hold the cross-legs in their upright position at the proper distance apart. At each end the pole is undercut in both directions, producing a wedge-shaped end E', which is adapted to fit into the angle A', produced by the crossing of the legs A. Each wedge-shaped end also has a block F ar-

ranged thereon, said block being slotted 55 transversely from opposite sides, as shown at F', in order to receive the cross-legs A, and it will be noted that the said slots are arranged out of alinement with each other in order to be in proper position to receive the said legs, 60 as it will be understood that the legs are of the same thickness throughout their length, so that the connecting-pole can be arranged at any desired height.

The slots F' are of such width and so arranged that the legs A will fit snugly therein and after the lines have been stretched across and lengthwise of the device all danger of the device collapsing or any of the parts becoming disengaged entirely avoided. 70

It will thus be seen that I provide an exceedingly cheap, simple, and efficient form of foldable clothes-drier, as it will be readily understood that when the device is not in use the parts can be quickly and easily disengaged and packed away into a very small space. In use a clothes-line is run around the cross-legs, being supported by the hooks B, as shown in the drawings.

Having thus fully described my invention, 80 what I claim as new, and desire to secure by Letters Patent, is—

1. A clothes drier or rack comprising a connecting-pole having blocks at each end, slotted transversely, supporting cross-legs 85 adapted to fit into the said transverse slots and provided with means at their upper ends for receiving a clothes-line, the lower ends of the legs being connected to prevent displacement.

2. A folding clothes drier or rack comprising a pole having wedge-shaped ends and blocks arranged upon said ends, said blocks being slotted transversely from the opposite sides, cross-legs adapted to fit into the slots 95 of the block, the wedge-shaped ends of the poles being adapted to fit in the angle formed by the intersection of the cross-legs, hooks carried by the said cross-legs upon their upper portions, cords connecting the lower ends of 100 the legs, and a clothes-line extending around the upper portion of the cross-legs and engaging the hooks, as set forth.

DOMINIC SHERLOCK.
